Alexander Rabinovich(57) **CLAIM**

The ornamental design for an inner insert for a pneumatic tyre as shown and described.

DESCRIPTION

6. Inner insert for pneumatic tyre

6.1 : Perspective

6.2 : Left

6.3 : Right

6.4 : Front

6.5 : Back

6.6 : Cross sectional

Fig. 6.1 are perspective views of the designs; fig. 6.2 are left views thereof; fig. 6.3 are right views thereof; fig. 6.4 are front views thereof; fig. 6.5 are back views thereof; fig. 6.6 are cross-sectional views taken along lines 6-6 of fig. 6.3.
